United States Patent Office

Des. 219,515

Patented Dec. 22, 1970

219,515

EDUCATIONAL TOY

Edward Hurley Levitt, Kowloon, Hong Kong, assignor
to Crown Industrial Co. Ltd., a company of Hong Kong

Filed July 28, 1969, Ser. No. 18,432

Term of patent 14 years

Int. Cl. D19—08

U.S. Cl. D25—1

FIG. 1

FIG. 2

FIG. 3

FIG. 5

FIG. 4

FIG. 1 is a front elevational view of my educational toy, showing my new design.

FIG. 2 is a side elevational view of the educational toy;

FIG. 3 is a top plan view thereof;

FIG. 4 is a rear elevational view of the educational toy; and

FIG. 5 is a bottom plan view.

The opposite side elevational view of the educational toy is a mirror image of FIG. 2.

I claim:

The ornamental design for an educational toy, as shown and described.
